US00D921069S

(12) **United States Design Patent** (10) Patent No.: **US D921,069 S**
Kape (45) Date of Patent: **** Jun. 1, 2021**

(54) **MACHINE FOR THE DEVELOPMENT AND PRODUCTION OF SOLID PHARMACEUTICAL PRODUCTS**

(71) Applicant: **Glatt GmbH**, Binzen (DE)

(72) Inventor: **Adrian Kape**, Binzen (DE)

(73) Assignee: **Glatt GmbH**, Binzen (DE)

(**) Term: **15 Years**

(21) Appl. No.: **35/507,752**

(22) Filed: **May 3, 2019**

(80) **Hague Agreement Data**

Int. Filing Date: **May 3, 2019**

Int. Reg. No.: **DM/203925**

Int. Reg. Date: **May 3, 2019**

Int. Reg. Pub. Date: **Nov. 15, 2019**

(51) LOC (13) Cl. **15-09**

(52) **U.S. Cl.**

USPC **D15/122; D15/145**

CPC **G07F 9/026** (2013.01)

(58) **Field of Classification Search**

USPC D15/122, 145, 146; 53/52, 131.2, 154,

53/168, 237, 268; 221/2, 9, 83, 154, 125

CPC G06Q 20/206; G07F 9/026; G07F 11/16;

G07F 17/0092; G07F 7/02; G07F 11/165;

(57) **CLAIM**

The ornamental design for machine for the development and production of solid pharmaceutical products, as shown and described.

DESCRIPTION

2. Machine for the development and production of solid pharmaceutical products

2.1 : Perspective

2.2 : Front

2.3 : Back

2.4 : Right

2.5 : Left

2.6 : Perspective

1 Claim, 6 Drawing Sheets
